(57) **CLAIM**

The ornamental design for a portion of an electronic housing with corner illumination, as shown and described.

DESCRIPTION

FIG. 1 is a front perspective view of an electronic housing with corner illumination showing our new design in a non-illuminated state;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is bottom view thereof;

FIG. 8 is a front perspective view of the electronic housing with corner illumination of FIGS. 1-7 in an illuminated state;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken line showing of various features of the portion of the electronic housing with corner illumination are for environmental purposes only and form no part of the claimed design.

In FIGS. 7 & 14, the unshaded surface that directly adjoins the claimed solid line edge forms no part of the claimed design.

The radiating lines emanating from the vertical strip in FIGS. 8-14 represent illumination.
